UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed May 23, 1922. Serial No. 562,969.

To all whom it may concern:

Be it known that I, BURNHAM C. STICKNEY, a citizen of the United States, residing at Elizabeth, in the county of Union and 5 State of New Jersey, have invented certain new and useful Improvements in Typewriting Machines, of which the following is a specification.

This invention relates to the application 10 of mechanism of the continuous billing or fan-fold type to bookkeeping machines of the Underwood-Hanson type, and is in the nature of an improvement on the invention disclosed in my prior application, Serial No. 15 489,990, filed August 5, 1921.

When fan-fold mechanism is applied to a bookkeeping machine of the type referred to, the webs must be guided above the usual housing of each set of denominational jacks, 20 thereby rendering it difficult to straighten the webs sufficiently under the platen to permit the carbons to be withdrawn by the usual carbon-carrier. Moreover, due to the mounting of the typewriting machine on the computer casing, provision must be made of a suitable support, different from that in the usual fan-fold machines, for the rear rail on which the rear end of the carbon-carrier track travels. Furthermore, it is desirable 25 to support the carbon-carrier track in such a manner as to permit access to the parts at the back of the machine.

In carrying out the invention, use is made at each end of the platen of an oversized 35 broad pinion for connecting the gear on the adjacent end of the platen axle with the similar gear on the stub-shaft journaled in the adjacent end of the carriage. By using oversized broad pinions, it is rendered possible to 40 locate the shafts, carrying the broad pinions and about which the platen-lifting frame swings, at such a position that the platen may be raised to a greater extent than in the ordinary fan-fold machine.

45 The front end of the carbon-carrier track may be pivotally supported immediately above the rear end of a jack-housing mounted at the rear of the typewriter. This housing slopes downwardly toward the rear, and 50 the front end of the carbon-carrier track may, therefore, be in a lower position than it would be if the front end of the track were mounted above the front end of the housing or still farther to the front. This 55 position of the forward end of the track also

renders the machine more open at the top so that access may readily be had to the denomination-selectors.

In said prior application, the rear rail on which the carbon-carrier track travels transversely of the machine is mounted on a bracket or support secured to the rear of the typewriter frame. Such an arrangement interferes, however, with access to the denomination-selecting mechanism and other parts at the rear of the typewriter frame. According to the present invention, the bracket, on which said rear rail is mounted, is supported on the stand on which the computer casing rests, thus providing sufficient room between the upper part of the bracket and the back of the bookkeeping machine to permit access thereto. Although the weight to be supported by said bracket is small, it is necessary to make said bracket of considerable strength to prevent the same from being bent out of shape by actual collisions therewith. The bracket or support for the rear rail may be so constructed that it may be attached to the usual form of stand for a bookkeeping machine without any change in the construction of the stand.

To support the front end of the carbon-carrier track, provision may be made of brackets, one for each side of the machine, so constructed that they may be set down over the rods which carry the usual denominational selectors. The brackets may be held in this position by means of angular members detachably secured thereto and extended under the usual brackets by which said rods are supported. The brackets for supporting the front end of the carbon-carrier track are arched sufficiently to permit them to pass over the housing for the denominational jacks, and they are connected at their rear ends by a cross-bar extending above the rear portion of the housing and the upper end of the casing for the usual thrust rods.

Provision may be made of brackets projecting forwardly from said cross-bar and having pivoted thereon the front cross-rod of the carbon-carrier track. Provision may also be made of forwardly-extending arms pivoted coaxially with the front cross-rod of the carbon-carrier track and connected at their forward ends by a rod or guide, which, when in its normal position, lies immediately above the rear edge of the usual rear

paper-table, the ends of said arms then resting on the rear paper-table. This rod serves as a guide over which the usual webs pass to the platen. The webs, in passing 5 from the carbon-carrier track to the rod at the forward ends of said arms, must be maintained at a sufficient height to pass over the raised front end of the housing of the denominational jacks, and for this 10 purpose, provision may be made of a bar connecting the two arms and lying immediately above the uppermost portion or peak of the housing. When a denominational selector is to be placed on the carriage or re- 15 moved therefrom, the frame comprising the two arms and the connecting rod and bar must be swung upwardly and rearwardly. It will be seen that, according to the present invention, the fan-fold mechanism at the rear 20 of the usual bookkeeping machine may be applied thereto without any change in the bookkeeping machine.

Other features and advantages will hereinafter appear.

25 In the accompanying drawings,

Figure 1 is a side view showing my invention applied to so much of an Underwood-Hanson book-keeping machine as is necessary for the purpose of illustration.

30 Figure 2 is a perspective view of the bracket for supporting the rail on which the rear portion of the carbon-carrier track travels.

35 Figure 3 is a rear view of the structure shown in Figure 1.

Figure 4 is a sectional side view showing the means for supporting the forward end of the carbon-carrier track and the means for guiding the webs over the housing for the 40 denominational jacks.

Figure 5 is a fragmentary sectional view showing the connection between the carbon-carrier and one of the rails of the track and also a brake to restrain the movement of the 45 carrier.

Figure 6 is a bottom view of the structure shown in Figure 5.

50 Figure 7 is a diagrammatic view, partly in section, showing the platen in raised position and the webs straightened thereunder.

Figure 8 is a top plan view of the structure shown in Figure 1, certain parts being broken away.

55 In a bookkeeping machine of the Underwood-Hanson type, a typewriter 11 having a frame 12 rests on the casing 13 of a computer 14, which is controlled by the numeral keys of the typewriter, and the computer casing 13 rests on a stand 14 comprising a top 15 and supporting posts or legs 16, of which the two legs on each side are connected by members 16a.

60 The typewriter 11 comprises a platen 17, mounted on a platen-axle 18, rotatably supported in a traveling carriage 19, which is

supported at its rear on a rail 20 fixed on the typewriter-frame 12. Associated with the platen is a rear paper-table 21 over which work-sheets or webs are directed to the bottom of the platen. When used as a part of the 70 bookkeeping machine, provision is made of brackets 22 attached to the rear of the typewriter-frame 12 at each side thereof and carrying at their upper ends a bar 23 on which may be supported one or more sets of denominational jacks (not shown) and a housing 24 for each set of such denominational jacks. Said housing 24 is highest at its forward end 75 and slopes downwardly toward the rear. At the rear of the housing 24, a casing 25 for the usual thrust rods (not shown) extends downwardly to the rear of the computer casing 13 and is attached thereto.

For use in a bookkeeping machine, the carriage is provided at its rear with brackets 26 extending rearwardly and outwardly and having upwardly-extending ends 27 in which are mounted a rod 28 along which a denominational selector 29 may be moved and a notched rod 30 having its notches at 80 letter-space distances, the denominational selector 29 being held in adjusted position by engagement of a tooth 31 thereon in one of the notches of the notched rod 30. When the carriage is traveling through a computing 85 zone, a tappet (not shown) carried by the denominational selector 29 engages successively the forward ends of the denominational jacks (not shown) pivotally mounted in housing 24, and selects the denominations 90 in which digits are to be indexed.

The computing mechanism and the denomination-selecting mechanism forming part thereof may be in general similar to that disclosed in the patent to Richard M. Becker, 105 No. 1,296,354, granted March 4, 1919.

Inasmuch as the present invention contemplates the use in a bookkeeping machine of the features of a continuous-billing or fan-fold machine, the axle 18 of the platen 17 is journaled in ends 32 of a platen-displacing frame 33, said ends 32 being pivoted on a shaft 34 at the front of and above the normal position of the platen-axle 18. The platen-axle is provided at each of its ends 110 with a gear 35, which meshes with a broad pinion 36 fixed on the shaft 34, and the broad pinion 36 also meshes with a gear 37 similar to gear 35 and fixed on the inner end 115 of a stub-shaft 38 journaled in the adjacent end of the carriage 19. The platen may be rotated by means of either of the finger-wheels 39 or by the usual line-spacing mechanism. When the webs, indicated in general 120 by 40, are to be straightened under the platen to permit the withdrawal of the interleaved carbons in the usual manner the platen is swung upwardly above the shaft 34 to the position shown in Figure 7, the webs 40 then being drawn forward and 125 130

gaged by means of the usual gage 41 adjustable on the gage-bar 42 mounted on a front collating table 43 which forms part of the platen-displacing frame.

5 In order to displace the platen 17 upwardly to a sufficient extent to straighten thereunder the webs 40 used with the fan-fold mechanism, the broad pinions 36, which may be described as oversized, are very 10 much larger than in the usual fan-fold machine, thus permitting the shaft 34 to be positioned at a greater distance than usual from the platen-axle 18, so that the platen may be displaced upwardly to the desired 15 extent. Such increased displacement of the platen is rendered necessary by the position of the housing 24 above which the webs 40 must pass.

At the rear of the machine, provision 20 may be made of a carbon-carrier 44 mounted for forward and rearward movement on a track or frame 45 comprising a front member 46, a rear member 47 and a plurality of connecting members 48, two of said members 25 48 having on the upper sides thereof rails 49, with each one of which co-operate grooved rolls 50, as shown in Figures 5 and 6. The rolls 50 are rotatably mounted in the ends of members 50^a secured to the lower 30 face of and at opposite sides of a base-plate 51 of the carbon-carrier, and the movement of the carbon-carrier 44 along the rails 49 is resisted to a certain extent by spring brakes 52 bearing on the lower faces of the rails 35 49. The carbon-carrier may be moved to the rear by means of a handle 49^a of the usual form.

To support the carbon-carrier track 45 at its forward end, provision is made of brackets 53 which may be readily attached to and removed from the rods 28 and 30, each bracket being cut away to form a slot 54 to receive the rod 28 and also cut away to form a shoulder 55 to rest on the top of the rod 30. It is a desideratum to provide 45 means for attaching the brackets 53 to the typewriter carriage without changing the usual construction of the carriage and without making any openings therein to receive 50 screws or other attaching devices. To this end, the brackets 53 are held in position on the rods 28 and 30 by means of angle-plates or clamps 56 placed on the outside of the upwardly-turned ends 27 of the brackets 26 55 and having their lower ends fitting under the laterally extending portions of the brackets 26, each of the plates 56 bridging over the upright end 27 of the corresponding bracket 26 and being connected to the 60 latter by suitable fastening means, such as bolts 58.

The brackets 53 are arched so as to pass over the housing 24 during the lateral movements of the carriage and terminate at 65 points slightly above the level of the rear

end of the housing 24. The rear ends of the brackets 53 are connected by a cross-bar 59 which extends over the rear end of the housing 24 and furnishes a support for the forward end of the carbon-carrier track 45, the 70 front member 46 of the latter being pivotally mounted on brackets 60 secured to the bar 59 and extending slightly to the front thereof.

As a result of mounting the front member 75 46 of the track 45 in the position described, there is a considerable gap between said front member 46 and the rear end of the paper-table 21, and it becomes necessary to provide means for guiding the webs 40 80 above the raised front portion of the housing 24. For this purpose, provision is made of arms 61 pivoted on the brackets 60, so as to turn about the same axis as the front member 46, and normally extending forwardly with their down-turned forward ends resting on the rear paper-table 21. Supported at its ends on the arms 61 is a bar 62 which lies directly over the raised 85 forward end of the housing 24, thus preventing any interference between the latter with the webs 40 when the carriage is moved laterally of the machine. Without this bar 62, the webs 40 would be liable to be caught on the sides of the housing 24 or on the 90 usual screws 63 which project from the upper surface thereof. The arms 61 are connected at their forward ends by a rod 64 which also serves as a guide for the webs from which they pass downwardly between 95 the rear paper-table 21 and the platen 17. Side gages 65 may be mounted on the rod 64 and may be secured in adjusted position thereon by screws 66. The arms 61, the bar 62 and the rod 64 constitute a frame or 100 intermediate web-guide which may be swung upwardly and rearwardly to permit adjustment of the denominational selector 29 along rods 28 and 30 when such adjustment is to be effected. It will be evident that, 105 when the frame comprising the arms 61 is swung rearwardly, the curved upper edges will be brought into engagement with the upper face of the cross-bar 59, and that the frame may be left in this position until it 110 is desired to restore it to its normal position.

At its rear end, the carbon-carrier track may be provided with a guide-rod 67 on which are adjustably mounted two side 115 gages 68, one of which is provided with an overhanging portion 69 to prevent the webs 40 from being lifted above the side gages 68.

At its rear, the track 45 is supported by a rail 70 on which run rolls 71 rotatably 120 mounted on arms 72 extending downwardly from the frame 45 and having their lower ends 74 extending beneath the rail 70 so as to maintain the rolls 71 in contact with the rail 70. In said prior application, 125 130

Serial No. 489,990, the rail corresponding to rail 70 of the present machine was supported by a bracket or brackets attached to the typewriter frame at its rear, an arrangement which rendered difficult access to the rear of the typewriting machine. To overcome this disadvantage, the support 75 for said rail 70 is mounted on the stand on which the computer casing 13 rests, thereby 10 spacing the upper end of the support 75 sufficiently to the rear to permit ready access to the back of the typewriter and the computer casing.

The support 75 comprises a bar 76 to be 15 positioned on the top 15 of the stand 14^a and provided with openings 77 which may be brought into register with openings 78 and 79 in the top 15 and in motor-frame 80, so that the motor-frame 80 and the bar 20 76 may be held in position by screws 81 extending through said openings 77 and 78 and threaded into the motor-frame 80. In machines of this class, the motor-frames are usually attached to the stand by screws 25 in the position shown, and, in order to secure the cross-bar 76 in the position described, it is necessary merely to use screws 81 of greater length than ordinary. The support 75 also comprises side members 82 provided at their lower ends with laterally-extending hooks 83 which may be moved 30 into position to embrace the adjacent legs 16 by movement inwardly from the sides, the side members 82 being held in final position on said legs 16 by means of set-screws 84 threaded in the sides of said hooks, so that they may be tightened against the legs 16 to clamp the side members 82 in 35 position. The side members 82 are also connected by means of screws 85 with brackets 86 extending rearwardly from the ends of the cross-bar 76.

To further strengthen the support 75, provision is made of a cross-bar 87 near the 45 upper ends of the side members 82 and secured thereto by screws 88. The rail 70 is provided with plates 89 extending therefrom and so spaced as to correspond with the spacing of the upper ends of the side members 82, so that the plates 89 may be 50 placed on the upper ends of the side members 82 and secured thereto by suitable fastening devices 90. As herein disclosed, the plates 89 are provided with ribs 91 to enter 55 grooves 92 in the upper ends of the side members 82. It should be noted that the structure of the support 75 is such that it may be attached to the stand 14^a without changing the structure of the latter in any 60 respect, the lower ends of the side members 82 being clamped on the legs 16 and the bar 76 being secured to the top of the table by screws 81 passing through the same openings as the usual screws for supporting the 65 motor-frame 80.

Although the weight to be supported by the rail 70 is comparatively small, it is necessary to make the support 75 of considerable strength so as to prevent bending or breakage of the same by accidental collision therewith, the support 75 extending in such a direction from the stand that it is likely to be struck accidentally especially when the track 45 is removed from the rail 70.

It should be understood that the engaging portions of the typewriter-frame 12, the computer-casing 13 and the top 15 of the stand 14^a are so constructed that, when assembled as shown in Figure 7, the movement of the carriage will be parallel to the rail 70.

Variations may be resorted to within the scope of the invention, and portions of the improvements may be used without others.

Having thus described my invention, I claim:

1. The combination with a typewriter carriage comprising a rear paper-table, of a revoluble platen normally cooperating with said paper-table, a platen-displacing frame mounted in said carriage, a carbon-carrier to retract carbon-sheets along work-webs when the latter are straightened under the platen, a carbon-carrier track connected with the carriage to travel therewith and having its front end spaced rearwardly from the rear edge of said paper-table, and a web-guide to guide the webs from the carbon-carrier track to the rear paper-table, 90 said web-guide being pivotally mounted so that it may be swung away from its normal position to permit access downwardly between said paper-table and said carbon-carrier track.

2. The combination with a typewriter carriage comprising a rear paper-table, of a revoluble platen normally cooperating with said paper-table, a platen-displacing frame mounted in said carriage, a carbon-carrier to retract carbon-sheets along work-webs when the latter are straightened under the platen, a carbon-carrier track, means for connecting the forward end of said carbon-carrier track with the carriage, said connecting means comprising arms attached to the carriage at each side thereof and extending rearwardly therefrom, a cross-bar connecting said arms near their rear ends, the front end of said carbon-carrier track being 100 mounted on said cross-bar, and a web-guide to support said webs between the track and the paper-table, said web-guide being pivoted on said cross-bar so that it may be 110 swung upwardly and rearwardly to permit access downwardly between said track and said paper-table.

3. The combination with a stand for a combined typewriting and computing machine having fan-fold mechanism applied 130

thereto, said stand comprising a top and legs, of a rail to support the rear of the carbon-carrier track of said fan-fold mechanism and a support for said rail comprising
 5 a member secured on said top adjacent its rear edge and having rearwardly-extending brackets, side members having provisions at their lower ends whereby they may be clamped to the rear legs of said stand, and
 10 means to secure said side members to said brackets, said rail being secured to the upper ends of said side members.

4. The combination with a stand for a combined typewriting and computing machine having fan-fold mechanism applied thereto, said stand comprising a top and legs, of a rail to support the rear of the carbon-carrier track of said fan-fold mechanism and a support for said rail comprising
 20 a member secured on said top adjacent its rear edge and having rearwardly-extending brackets, side members having provisions at their lower ends whereby they may be clamped to the rear legs of said stand, and
 25 means to secure said side members to said brackets, said rail being secured to the upper ends of said side members, and a cross-bar to connect said side members near their upper ends.

30 5. In combination, an upwardly-displaceable platen, a traveling carriage therefor, computing mechanism projecting upwardly above the rear of the carriage and co-operating with the carriage, a reciprocable carbon-carrier at the rear of the platen, a carbon-carrier-supporting table extending at its front over such upwardly-projecting computing mechanism, and over the forward edge of which work-plies and interleaved
 35 carbons are bent sharply and carried downwardly a considerable distance to the bottom of the platen, platen-line-spacing means on the carriage, and means including an oversize pinion to maintain a connection between said line-spacing means and the platen while permitting the platen to be raised to so great a height as to enable the work-plies to be brought substantially level over said table and under said platen preparatory to effecting a relative shifting of the work-plies and interleaved carbon-sheets.

40 6. In combination, a platen, a traveling carriage therefor, comprising an inclined rear paper-table, a denomination-selector mounted on said carriage at the rear of and adjacent the upper edge of the rear paper-table, denomination-selecting mechanism having a housing with its forward end overlying said denomination-selector, a carbon-carrier to retract carbon-sheets interleaved between webs passing through the carbon-carrier, a carbon-carrier track supported at its front adjacent the rear of said housing, the webs passing above said housing, a
 45 platen normally co-operating with said rear

paper-table, a platen-axle on which said platen is fixed, a gear on one end of said axle, a second gear of the same size adjacent the first and rotatably mounted in the adjacent end of the carriage, an oversized 70 broad pinion meshing with both of said gears, a shaft journaled in the ends of the carriage and on which the broad pinion is fixed, and a platen-displacing frame pivotally mounted on said shaft and having the 75 platen-axle journaled therein, the use of said oversized pinion permitting said shaft to be positioned far enough from the normal position of the platen-axle, so that, upon swinging the platen-displacing frame to its displaced position, the platen will be lifted sufficiently to permit the webs to be straightened above said housing and under said platen.

7. In combination, a platen, a traveling carriage therefor, comprising an inclined rear paper-table, a denomination-selector mounted on said carriage at the rear of and adjacent the upper edge of the rear paper-table, denomination-selecting mechanism 90 having a housing with its forward end overlying said denomination-selector, a carbon-carrier to retract carbon-sheets interleaved between webs passing through the carbon-carrier, a carbon-carrier track supported at 95 its front adjacent the rear of said housing, the webs passing above said housing, a web-support pivotally connected at its rear with the forward end of said track and normally resting on said rear paper-table at its forward end, said web-support serving to prevent engagement between the side edges of the webs and said housing, and being swung upwardly to permit access to the denomination-selector when the latter is to be set in 100 a new position, a platen normally co-operating with said rear paper-table, and platen-displacing means to give an abnormal displacing movement to said platen to permit the straightening thereunder of the 110 webs extending from said carbon-carrier over said web-support.

8. The combination with a typewriter comprising a carriage, a computer on which said typewriter is mounted, operative connections between said typewriter and computer including denomination-selecting means at the rear of the typewriter and computer, and a stand for said computer, of a carbon-carrier, a track therefor connected at its 115 forward end with the carriage to travel therewith and to direct webs, passing through the carbon-carrier, over the denomination-selecting means to the platen, a rail on which the rear end of said track travels, and a 120 bracket for carrying said rail at its upper end mounted on said stand at the rear thereof and extending rearwardly and upwardly from the stand to provide sufficient space in front of the bracket to permit access from 125 130

- the side and rear to the denomination-selecting means and adjacent parts for manipulation, adjustment, repairing, cleaning and the like.
- 5 9. In a combined typewriting and computing machine in which numbers are indexed digit by digit and then computed, the combination with a traveling carriage, of transverse rods supported on said carriage at the rear thereof, a housing for denominational jacks having its forward end higher than said rods to permit a denomination-selector on the latter to engage the forward ends of jacks in the housing, two brackets having their forward ends cut away to permit them to be set down over said rods, said brackets being arched to permit them to pass over said housing and having their rear ends substantially at the level of the rear edge of the top of said housing, a cross-bar joining the rear ends of said brackets, a carbon-carrier track having a front cross-member connected with said cross-bar, a web-supporting frame comprising arms pivoted on said cross-bar and having their forward ends normally resting on said carriage. 70
- 10 15 20 25 30 35 40 45 50 55 60 65 70 75 80 85 90 95 100 105 110 115 120 125 130
10. In a combined typewriting and computing machine in which numbers are indexed digit by digit and then computed, the combination with a traveling carriage, of transverse rods supported on said carriage at the rear thereof, a housing for denominational jacks having its forward end higher than said rods to permit a denomination-selector on the latter to engage the forward ends of jacks in the housing, two brackets having their forward ends cut away to permit them to be set down over said rods, said brackets being arched to permit them to pass over said housing and having their rear ends substantially at the level of the rear edge of the top of said housing, a carbon-carrier track having a front cross-member connected with said brackets, and a web-support pivotally supported on said brackets at its rear and at its front normally resting on said carriage. 95
11. In a combined typewriting and computing machine in which numbers are indexed digit by digit and then computed, the combination with a traveling carriage comprising a rear paper-table, of transverse rods supported on said carriage at the rear thereof, a housing for denominational jacks having its forward end higher than said rods to permit a denomination-selector on the latter to engage the forward ends of jacks in the housing, two brackets having their forward ends cut away to permit them to be set down over said rods, said brackets being arched to permit them to pass over said housing and having their rear ends substantially at the level of the rear edge of the top of said housing, a cross-bar joining the rear ends of said brackets, a carbon-carrier track having a front cross-member connected with said cross-bar, a web-supporting frame comprising arms pivoted on said cross-bar and having their forward ends normally resting on said carriage, and a cross-bar connecting the rear ends of said brackets and positioned slightly above the rear end of the housing, and means whereby the forward end of said track is supported on said cross-bar. 115
12. In a combined typewriting and computing machine in which numbers are indexed digit by digit and then computed, the combination with a traveling carriage, of transverse rods supported on said carriage at the rear thereof, a housing for denominational jacks having its forward end higher than said rods to permit a denomination-selector on the latter to engage the forward ends of jacks in the housing, two brackets having their forward ends cut away to permit them to be set down over said rods, said brackets being arched to permit them to pass over said housing and having their rear ends substantially at the level of the rear edge of the top of said housing, a carbon-carrier track having a front cross-member connected with said cross-bar, a web-supporting frame comprising arms pivoted on said cross-bar and having their forward ends normally resting on said carriage, and a guide-rod connecting said arms and normally lying above the upper edge of said rear paper-table. 80
13. In a combined typewriting and computing machine in which a denomination-selector is given a letter-space movement beneath the raised forward end of a denominational jack-housing at the top of the machine, in combination, a carriage, two transverse rods supported by said carriage at its rear and furnishing a support for the denomination-selector, a carbon-carrier track, and means for connecting the forward end of the carbon-carrier track with said carriage, said connecting means comprising a bracket at each end of the carriage and removably positioned on said rods, means connected with said brackets to secure said brackets on said rods, said brackets being arched to permit them to pass over said housing and terminating adjacent the rear end of the latter, a cross-bar connecting the rear ends of said brackets and positioned slightly above the rear end of the housing, and means whereby the forward end of said track is supported on said cross-bar. 105
14. In a combined typewriting and computing machine in which a denomination-selector is given a letter-space movement beneath the raised forward end of a denominational jack-housing at the top of the ma- 130

chine, in combination, a carriage, two transverse rods supported by said carriage at its rear and furnishing a support for the denomination-selector, a carbon-carrier track, 5 and means for connecting the forward end of the carbon-carrier track with said carriage, said connecting means comprising a bracket at each end of the carriage and removably positioned on said rods, means connected with said brackets to secure said brackets on said rods, said brackets being arched to permit them to pass over said housing and terminating adjacent the rear end of the latter, a cross-bar connecting 10 the rear ends of said brackets and positioned slightly above the rear end of the housing, means whereby the forward end of said track is supported on said cross-bar, arms pivotally mounted on said cross-bar 15 and having their forward ends normally resting on said carriage, and a web-supporting bar attached at its ends to said arms so as to lie over the highest portion of said housing to prevent interference with work-webs during movement of the carriage in 20 either direction.

15. In a combined typewriting and computing machine in which a denomination-selector is given a letter-space movement 30 beneath the raised forward end of a denominational jack-housing at the top of the machine, in combination, a carriage, two transverse rods supported by said carriage at its rear and furnishing a support for the 35 denomination-selector, a carbon-carrier track, and means for connecting the forward end of the carbon-carrier track with said carriage, said connecting means comprising a bracket at each end of the carriage 40 and removably positioned on said rods, means connected with said brackets to secure said brackets on said rods, said brackets being arched to permit them to pass over said housing and terminating 45 adjacent the rear end of the latter, a cross-bar connecting the rear ends of said brackets and positioned slightly above the rear end of the housing, means whereby the forward end of said track is supported on said 50 cross-bar, arms pivotally mounted on said cross-bar and having their forward ends normally resting on said carriage, a web-supporting bar attached at its ends to said arms so as to lie over the highest portion of 55 said housing to prevent interference with work-webs during movement of the carriage in either direction, and a rod joining the forward ends of said arms and serving as a guide from which the webs pass downward- 60 ly to the platen.

16. The combination with a stand for a combined typewriting and computing machine provided with fan-fold mechanism, comprising a carbon-carrier track and a rail 65 on which the rear end of said track travels,

and a motor for operating said machine, said stand having a top, to the underside of which, at its rear, the motor is attached by screws passing through openings in said top and threaded into openings in the motor frame, and four legs to support said top, of a support for said rail comprising a cross-member having openings which may be brought into register with said openings in the top, so that said cross-member may 70 be held in position on the top by screws passing through the openings in said cross-member and said top, and threaded into the openings in said motor frame, side members provided with hooks to pass over the rear 75 legs of said stand when moved laterally, set screws in the sides of the hooks to engage the legs and hold the side members in position, screws connecting said side members and said cross-member, and a cross-bar connecting said side members near their upper 80 ends, said rail being attached to said side members at their upper ends.

17. In a fan-fold typewriting machine, in combination, a platen, a carriage for said platen, and a rearward extension of said carriage comprising a main portion spaced rearwardly from said carriage and a shiftable portion between said main portion and the carriage which may be shifted from its 90 normal position to permit access downwardly between said main portion and the carriage.

18. In a fan-fold typewriting machine, in combination, a platen, a carriage for said platen, and a rearward extension of said carriage comprising a main portion spaced rearwardly from said carriage and a shiftable portion between said main portion and the carriage which may be shifted from its 95 normal position to permit access downwardly between said main portion and the carriage, said shiftable portion being pivotally supported at the forward edge of said main portion and normally having its forward 100 end resting on the carriage.

19. In a fan-fold typewriting machine, the combination with a platen and a carriage therefor having a rear paper-table, of a rearward extension of said carriage over 115 which webs may be fed to the carriage, said extension being spaced from said rear paper-table, and an intermediate web-guide pivoted at its rear adjacent the forward end of said extension and normally resting on said carriage at its forward end, said intermediate web-guide being swung upwardly from obstructing position when it is desired to have access downwardly between said extension and said rear-paper-table.

20. In a fan-fold typewriting machine, the combination with a platen and a carriage therefor having a rear paper-table, of a rearward extension of said carriage over 120 which webs may be fed to the carriage, said 125

extension being spaced from said rear paper-table, and an intermediate web-guide to direct the webs from said extension over the rear edge of said paper-table, said web-guide being so supported that it may be shifted from obstructing position to permit access downwardly between said extension and said paper-table.

21. In a fan-fold typewriting machine, 10 the combination with a carbon-carrier, of a rail at each side of and beneath the same, grooved rolls pivotally connected with said

carbon-carrier and engaging said rails on opposite sides thereof, and a leaf-spring connected with said carbon-carrier on the 15 lower side thereof adjacent each rail and engaging the upper side of the latter to prevent accidental movement of the carbon-carrier.

BURNHAM C. STICKNEY.
